SEPARABLE FASTENER

Frank G. Manson, Dayton, Ohio, assignor to
Hookless Fastener Company, Meadville, Pa., a
corporation of Pennsylvania

Application September 6, 1932, Serial No. 631,811

7 Claims. (Cl. 24—205)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to separable fasteners and more in particular to that type of fastener for garments and other purposes in which two separable flexible stringers may be connected and disconnected by a sliding device mounted on both 10 of said stringers, cooperating with interlocking members attached thereto, the connecting or locking being effected by a movement of the slider device in one direction and the disconnecting or unlocking by an opposite movement thereof.

15 The object of the present invention is to provide a novel detachable connecting means for the two flexible stringers of a separable fastener of the interlocking type, which will enable the quick and convenient attaching and detaching of opposing edges on a garment or other device to which the stringers may be attached and, accordingly, the novel connecting means is formed of 20 two separable parts that are attached to adjacent ends of the stringers and are provided with complementary retaining portions, one of said 25 separable parts being adapted to pass laterally within the sliding device for effecting a partial locking engagement between the retaining portions and being provided with means that 30 operate with the slider to effect a positive actuation of said portions into fully locked position by the movement of the slider in the direction of locking the interlocking members. The retaining or end connecting portions of the separable 35 parts may be made as separate elements if desired, but are preferably made integral with their respective parts, one of which is a socket or receiving member and the other is an entering member. The receiving member is preferably of 40 the thickness of the teeth throughout a greater portion of its length and is formed at its outer end with an enlarged portion that constitutes a stop for the sliding device and with a portion having an opening to receive a complementary hook 45 or wedging portion formed at one end of the entering member whose other end is formed with a head having a cam surface and a socket to receive the beaded edge of the stringer, the head being of the thickness of the teeth. Intermediate 50 of its ends the entering member is formed of a thickness less than the space between the flanged side walls of the sliding device for a length slightly greater than the length of these walls. On that side of the sliding device corresponding to 55 that of the entering member, the flanged side

walls are cut away for a portion of their length to allow the head end together with the intermediate portion of the entering member to pass laterally into the sliding device when the two parts of the connection are being secured together.

In the drawings:

Fig. 1 is a fractional view of two flexible stringers showing two separable parts embodying my invention with the sliding device shown in 10 cross-section and in the fully locked position of the separable parts;

Fig. 2 is an end view looking from left to right of Fig. 1;

Fig. 3 is a detail view showing the separable 15 parts in their initial engagement with the sliding device in the position to receive the entering member;

Fig. 4 is a view similar to Fig. 3 showing the 20 sliding device moved to a position in engagement with the entering member for directing the same into fully locked position;

Fig. 5 is a section taken along the line 5—5 of Fig. 1;

Fig. 6 is an edge view of the sliding device 25 looking from the upper side of Fig. 1;

Figs. 7 and 8 are blanks from which the entering and receiving members respectively shown in Fig. 1 are formed;

Fig. 9 is a view similar to Fig. 1 showing a 30 modified form of the separable parts;

Fig. 10 is a sectional view taken along the line 10—10 of Fig. 9;

Fig. 11 is a longitudinal sectional view taken along the line 11—11 of Fig. 9;

Figs. 12, 13 and 14 are views showing progressive positions of the separable parts and the slider in the operation of disengaging of the separable parts;

Figs. 15 and 16 are detail views of blanks from 40 which the entering and receiving members respectively shown in Fig. 9 are formed;

Fig. 17 is a view similar to Fig. 1 showing a further variation of my invention;

Fig. 18 is a partial end view of Fig. 17;

Fig. 19 is a fractional detail view showing the engaging portions of the separable parts in section; and

Figs. 20 and 21 are views showing blanks from 50 which the entering and receiving members respectively are formed.

Fig. 22 is a perspective view of the end connecting parts in the form shown in Figs. 1 to 8 inclusive;

Fig. 23 is a perspective view of a slider adapted 55

for use with the form shown in Figs. 1 to 8 inclusive;

Fig. 24 is a perspective view of the end connecting parts for the modification shown in Figs. 9 to 16 inclusive;

Fig. 25 is a perspective view of the end connecting parts for the modification shown in Figs. 17 to 21 inclusive;

Fig. 26 is a perspective view of a slider adapted for use with the form of invention shown in Figs. 9 to 16 inclusive.

Referring to Figs. 1 to 8 of the drawings, the numerals 10 and 12 designate stringers preferably made of woven material having secured thereto cords 14 and 16 respectively to form beaded edges to which the opposed series of locking elements 18 and 20 are respectively connected. Stringer 12 is provided at one end with a receiving member 22, that cooperates with a complementary entering member 24 that is secured to one end of the stringer 10 to provide with receiving member 22 an end closure for the stringers. A sliding device 26 is carried by stringer 12 and is adapted to be positioned at the closure end to receive the entering member 24 and to effect a locking engagement between the receiving and entering members in a manner hereinafter described.

The receiving member 22 is preferably formed from a strip of sheet metal, from which a stamping as shown in Fig. 8 is cut, whose sides being provided with transverse aligned cuts 28 and 30 will allow the split portions of each side to be folded in opposite directions to form angular side plates 32 and jaws 34. As best shown in Fig. 22 these side plates are formed to provide a sheath 36 that is adapted to be securely clamped around the corded edge of the stringer 12 and with parallel extensions or tabs 38 that are spaced to receive therebetween the stringer 12 to which they are secured by a rivet 40 or the like. The sheath 36 is preferably of the thickness of the interlocking members so as to pass freely between the walls 42 and 44 of the sliding device 26 that is manually operated to lock and unlock the locking elements 18 and 20, by a to-and-fro movement, respectively. The jaws 34 are spaced and have their ends abutting to form a socket to receive a complementary engaging portion of the entering member. For purposes of preventing the sliding device from passing off the receiving member, the jaws are formed to have an overall dimension greater than the spacing between the walls and thus serve as a stop to prevent the removal of the sliding device from stringer 12 at that end.

The entering member is also formed from a piece of sheet metal, from which a blank as shown in Fig. 7 is punched and formed. The sides of the blank are L-shaped and folded back upon themselves to form an L-shaped member with side plates 46 and tabs 48 in spaced relation to receive the end of stringer 10 to which the tabs 48 are attached by a rivet 50. The side plates are similarly shaped and provided with lugs 52. In their folded position they provide an engaging hook formed by lugs 52, a spacer portion 54 and a camming head portion 56.

The engaging portion 52 is hook shaped and extends along the inner side and from the outer end of the L-shaped member and is adapted to engage with the socket formed by arms 34 of the receiving member in such a manner that the inner sides of the receiving and entering members will be capable of assuming a parallel relation in the locked position thereof and relative longitudinal movement of these parts will be pre-

vented so that the interlocking elements next adjacent these parts will assume the proper position for interlocking engagement. The thickness of the engaging portion 52 is such that it will freely pass between the flanged sides 58 and 60 of the sliding device.

The spacer portion 54 is preferably a continuation of the engaging portion and is longer than the spaced flanged sides 58 and 60 and thin enough to pass freely therebetween.

The camming head portion 56 is formed by making the sides 46 rounded at their upper ends and laterally projecting from that portion of the sides that constitutes the spacer portion. The face 62 of the cam is arcuate. The rounded sides 15 of the head portion are sufficiently spaced to constitute a sheath for the stringer and the end of the cord 14 which terminates short of the stringer end, which is cut away along its inner lower edge corresponding to the position of the spacer portion. The camming portion of the entering member has a thickness greater than the space between the flanged sides of the slider but less than the space between the walls 20 42 and 44.

As shown in Fig. 23, the flanged sides 58 and 60 of the slider have cut away portions 61, which extend for a sufficient length so that the head portion 56 may freely pass between the walls 42 and 44. It will be obvious that when the sliding 30 device is moved forward the entering member will be permitted to move laterally into the sliding device and the hooked end will be actuated in fully locked position by the coaction of the flanged sides 58 and 60 and the cam surface 62. When the sliding device is moved to its lowermost limit of travel and the opposed interlocking members are disengaged the stringer 10 may be readily detached from the stringer 12 by a lateral movement of the entering member through and away 40 from the sliding device.

In locking the ends of the stringers together the sliding device is passed over the receiving member and is brought to rest by its outer end abutting against the jaws of the socket, the entering member is then passed laterally and at an angle into the sliding device with the hook in partial engagement with the socket and with the head portion partially within the sliding device. By moving the sliding device forward, the hook 50 will be actuated into complete engagement or locked position with the socket by the camming effect of the cam surface and the inner faces of its corresponding flanged side walls and the two separable parts will be brought into substantially 55 parallel relation with each other and the inner edges of the flexible stringers.

In Figs. 9 to 16 I have shown a modification of my invention, in which the entering member 64, except for its end engaging portion 66, is similar 60 in its construction to the entering member 24. It will be observed in Fig. 15 that the blank from which the entering member is formed is provided with a pair of tabs 68. After folding the sides 70 upon themselves the tabs 68 are reversely bent 65 upon themselves along the lines 72 and 74 in opposite directions to provide lateral flanges 76 and 78, which have an arcuate form as shown in Fig. 24 and serve as guides and cooperate with other portions of the receiving and entering members 70 for locking the same together. The flanges preferably, but not necessarily, extend across the width of the sliding device for a purpose herein-after described.

In this variation the receiving member 80 is 75

formed from a blank, as shown in Fig. 16, having similar shaped tabs 82 and 84 reversely arranged and provided with a series of upwardly extending lugs 86 and 88 respectively so that in folding the blank along the line 90 the tabs will be parallel, the lugs of the one tab abutting the lugs of the other tab, and with the edges of the tabs lying in substantially the same vertical plane as shown in Figs. 10 and 24. The lugs are arranged to lie in an arcuate path and serve as a guide or stop to limit the movement of the entering member, the spacer portion 92 of which is adapted to be received in the space between the tabs 82 and 84. These tabs are provided along their corresponding inner and outer edges with cammed surfaces 94 and 96 respectively so that when the spacer portion of the entering member is inserted between the tabs, the flanges 76 and 78 will first engage their respective cam surfaces 94 at a point inwardly thereof with the lower edge of the spacer contacting with the lowermost part of the lugs, while the cammed surfaces 62 of the head portion 56 will engage with their respective surfaces 96 at a point outwardly thereof and as the entering member is turned the pivot point of the entering member changes along the surface of the tabs until the flanges bear along the entire surface against the cam surfaces 94 and the cam surfaces 62 will have moved along their corresponding surfaces 96 to effect a wedging or locking engagement between the receiving and entering members.

The slider member used with this form of the invention is shown in Fig. 26 and is constructed identical to that above described in connection with Figs. 1 to 8 except that its outer end is formed with an arcuate portion 98' corresponding to the edges 94.

In the operation of this device the slider is moved to a position where it is stopped by the engagement of the point of the tongue 98 of the slider with the surfaces or edges 96. The thickness of the tongue and the angular surfaces 100 hold the slider in a predetermined angular position corresponding to the angle which the entering member will most likely assume immediately prior to its insertion laterally between the flanges of the slider and the tabs of the receiving member as shown in Fig. 14. When the entering member is in this position, the flanges 76 and 78 are in engagement with the corresponding arcuate ends of both the slider device and the receiving member and as the entering member is turned by hand the sliding device moves upwardly, bringing the cut-away portions 61 out of registry with the cammed head portion 56, as shown in Fig. 13, and thus preventing the entering member from slipping out of partial engagement with the receiving member. A continued movement of the slider will cause the lateral flanges 58 and 60 to engage with the cammed surfaces 62, thus turning the entering member into completely locked position, as shown in Fig. 9.

A further modification of my invention is shown in Figs. 17 to 21. In this embodiment the receiving and entering members are constructed in a manner similar to that described in connection with Figs. 1 to 8, these members being formed from blanks as shown in Figs. 20 and 21 respectively.

The receiving and entering blanks are formed with cut-out portions 102 and 104 respectively, so that when their sides are folded back upon themselves along the lines 106 and 108 notches are pro-

vided to receive complementary locking members 110 and 112 respectively. Locking member 110 is formed with spaced upper and lower flanges 114 that are disposed in overlapped relation with corresponding areas of the side plates of the entering member 116 and are secured thereto preferably by welding. Likewise locking member 112 is provided with upper and lower flanges 118 that are similarly secured to the side plates of the receiving member 120. The superposed upper and lower flanges of the locking member 112 serves as a stop for limiting the movement of the slider 26. The engaging portion 122 is similar in construction to the interlocking elements 18 and 20, whereas the engaging portion 124 is formed with two spaced jaws 126 and 128, the former being provided with a rounded recess, and the latter with a rounded projection between which the engaging portion 122 with its corresponding recess and projection is received. It will be obvious that disengagement of these interengaging portions can be effected only by an angular movement in a counter-clockwise direction.

It will be noted that in Figs. 1, 9 and 17 that the corded edge of the tape on the entering or male side of the connecting parts has its terminus inside the upper cylindrical part of the connecting member, as indicated by dotted lines in each instance.

It will be obvious that the invention is not to be restricted to the precise constructions herein shown and described since many of the details, such as the structure of the stringers interlocking members and slider will necessarily vary or may be varied according to the particular uses for which the fastener is designed and the construction of the end attaching means of each stringer may also be varied by those skilled in the art, it being intended that my invention be limited only by the scope of the claims.

I claim:

1. A fastener comprising a pair of separable and detachable stringers having interlocking members secured thereto in staggered relation, one of said stringers having one edge formed with a cord extending for a portion of its length to provide a corded portion and an uncorded portion, said uncorded portion and its adjacent corded portion having secured thereto an end connecting member and forming therewith flat and raised portions respectively, the other of said stringers having secured to one end complementary retaining means for said connecting member and a sliding device carried by said last-mentioned stringer and adapted to lock said interlocking members, said sliding device having a slotted side of irregular shape to laterally receive the flat and raised portions of said connecting member when said stringers are initially connected together.

2. A separable fastener comprising a pair of flexible stringers, cooperating interlocking members thereon and a separable end connection for said stringers comprising an entering member having a locking engaging portion, a spacer portion and a camming portion thicker than the spacer portion, a receiving member having a complementary locking engaging portion and a slider device provided with spaced lateral flanges adapted to cooperate with said entering and receiving members to effect a locking engagement therebetween, the space between said flanges for a portion of the length of the flanges admitting the spacer portion but preventing passage of the camming portion, and for the rest of

- its length being wide enough to admit the camming portion.
3. A separable fastener comprising a pair of flexible stringers, cooperating interlocking members thereon and a separable end connection for said stringers comprising an entering member having a locking engaging portion, a spacer portion and a camming portion, a receiving member having a complementary locking engaging portion and a slider device provided with spaced lateral flanges adapted to cooperate with said entering and receiving members to effect a locking engagement therebetween, the space between said flanges for a portion of its length on the side of the entering member being of such dimension as to permit a freedom of movement therebetween of the spacer portion but to prevent movement therebetween of the camming portion, said lateral flanges on one side of said slider terminating short of the forward end thereof to provide a space through which said entering member may freely pass.
4. A completely separable slide fastener comprising in combination a pair of flexible stringers having interlocking elements thereon, a slider including parallel plates separated at their edges by a slot for interlocking and disengaging the elements, a pair of end connecting members for the stringers, one member having an eye, and the other member having a hook engageable with the eye to effect a positive connection between the stringers, said members being of such width and thickness that they will enter the slider channel when connected together, the member having the hook being thinner than the width of the slot to allow it to pass laterally thru the slot in the slider while maintaining the positive connection with the eye member, said other connecting member having a cam engageable with the slider and arranged to move the members into parallel relation when the slider is moved off from the engaged connecting members.
5. A completely separable fastener comprising in combination a pair of flexible stringers, rows of complementary interlocking elements on the stringers, a slider for interlocking and disengaging the elements and having slots in its sides, a pair of separable end connecting members for the stringers, a pair of opposed shoulders on one of said members, a shoulder on the other member engageable with one of the shoulders on the first mentioned member to prevent relative longitudinal movement of the members in one direction, a second shoulder on said second-mentioned member engageable with the other shoulder on the first-mentioned member to prevent longitudinal movement in the opposite direction, said second-mentioned member being thinner than the thickness of the slots in said slider to allow it to pass laterally into the slider when the first-mentioned shoulders on both members are engaged, and means on the slider for drawing the second-mentioned shoulders on both members into engagement to positively lock the members against relative longitudinal movement before the slider can be moved off from said members to effect interlocking of the elements.
6. A fastener comprising, a pair of separable and detachable flexible stringers having interlocking members secured thereto in staggered relation, a slider adapted to slide on said members to lock and unlock the same according to its direction of movement, said slider comprising spaced wings having inturned lateral flanges constituting a guide on each side of the slider and having a narrow slot between said flanges, end attaching members for detachably connecting both stringers, one of said members being thinner in width and slightly greater in length than the slot and having a retaining element at one end and a cam element at the opposite end thereof, said retaining and cam elements being adapted respectively to cooperate with a complementary retaining element of said other end attaching member and the corresponding guide of said slide when passed laterally into the slot of the slide for effectively interlocking said retaining elements.
7. A separable fastener comprising a pair of flexible stringers, interlocking members on said stringers, a separable stringer end connection comprising an entering member having a locking engaging portion, a spacer portion and a camming portion, a receiving member having a complementary locking engaging portion and a slider for engaging and disengaging said interlocking members provided with spaced lateral flanges to receive therebetween the spacer portion of said entering member when said entering and receiving members are in partial engagement and to engage with the camming portion and guide said entering member into fully locked position with said receiving member.

FRANK G. MANSON.

CERTIFICATE OF CORRECTION.

Patent No. 1,984,378.

December 18, 1934.

FRANK G. MANSON.

It is hereby certified that the above numbered patent was erroneously issued to "Hookless Fastener Company, of Meadville, Pennsylvania, a corporation of Pennsylvania" as assignee of the entire interest in said invention, whereas said patent should have been issued to the inventor said Frank G. Manson, as shown by the records of assignments in this office; and that the said Letters Patent should be read with this correction therein that the same may conform to the record of the case in the Patent Office.

Signed and sealed this 5th day of March, A. D. 1935.

Acting Commissioner of Patents.

- its length being wide enough to admit the camming portion.
3. A separable fastener comprising a pair of flexible stringers, cooperating interlocking members thereon and a separable end connection for said stringers comprising an entering member having a locking engaging portion, a spacer portion and a camming portion, a receiving member having a complementary locking engaging portion and a slider device provided with spaced lateral flanges adapted to cooperate with said entering and receiving members to effect a locking engagement therebetween, the space between said flanges for a portion of its length on the side of the entering member being of such dimension as to permit a freedom of movement therebetween of the spacer portion but to prevent movement therebetween of the camming portion, said lateral flanges on one side of said slider terminating short of the forward end thereof to provide a space through which said entering member may freely pass.
4. A completely separable slide fastener comprising in combination a pair of flexible stringers having interlocking elements thereon, a slider including parallel plates separated at their edges by a slot for interlocking and disengaging the elements, a pair of end connecting members for the stringers, one member having an eye, and the other member having a hook engageable with the eye to effect a positive connection between the stringers, said members being of such width and thickness that they will enter the slider channel when connected together, the member having the hook being thinner than the width of the slot to allow it to pass laterally thru the slot in the slider while maintaining the positive connection with the eye member, said other connecting member having a cam engageable with the slider and arranged to move the members into parallel relation when the slider is moved off from the engaged connecting members.
5. A completely separable fastener comprising in combination a pair of flexible stringers, rows of complementary interlocking elements on the stringers, a slider for interlocking and disengaging the elements and having slots in its sides, a pair of separable end connecting members for the stringers, a pair of opposed shoulders on one of said members, a shoulder on the other member engageable with one of the shoulders on the first mentioned member to prevent relative longitudinal movement of the members in one direction, a second shoulder on said second-mentioned member engageable with the other shoulder on the first-mentioned member to prevent longitudinal movement in the opposite direction, said second-mentioned member being thinner than the thickness of the slots in said slider to allow it to pass laterally into the slider when the first-mentioned shoulders on both members are engaged, and means on the slider for drawing the second-mentioned shoulders on both members into engagement to positively lock the members against relative longitudinal movement before the slider can be moved off from said members to effect interlocking of the elements.
6. A fastener comprising, a pair of separable and detachable flexible stringers having interlocking members secured thereto in staggered relation, a slider adapted to slide on said members to lock and unlock the same according to its direction of movement, said slider comprising spaced wings having inturned lateral flanges constituting a guide on each side of the slider and having a narrow slot between said flanges, end attaching members for detachably connecting both stringers, one of said members being thinner in width and slightly greater in length than the slot and having a retaining element at one end and a cam element at the opposite end thereof, said retaining and cam elements being adapted respectively to cooperate with a complementary retaining element of said other end attaching member and the corresponding guide of said slide when passed laterally into the slot of the slide for effectively interlocking said retaining elements.
7. A separable fastener comprising a pair of flexible stringers, interlocking members on said stringers, a separable stringer end connection comprising an entering member having a locking engaging portion, a spacer portion and a camming portion, a receiving member having a complementary locking engaging portion and a slider for engaging and disengaging said interlocking members provided with spaced lateral flanges to receive therebetween the spacer portion of said entering member when said entering and receiving members are in partial engagement and to engage with the camming portion and guide said entering member into fully locked position with said receiving member.
